UNITED STATES PATENT OFFICE.

ANTHONY F. WILLIAMS, OF ROCHESTER, NEW YORK, ASSIGNOR TO NORTH EAST ELECTRIC COMPANY, OF ROCHESTER, NEW YORK, A CORPORATION OF NEW YORK.

TESTING ELECTRODE.

Application filed January 25, 1924. Serial No. 688,486.

This invention relates to electrodes of the kind used for testing electric apparatus for defects such as short-circuits and defective insulation. For this purpose it is customary 5 to use manually operated electrodes which are connected with a source of electricity, in series with a lamp or other indicator, and the tests are made by touching the contact-members of the electrodes to the commutator-bars, terminals and other parts of the apparatus under test.

For the purpose in question it is often necessary to use an electromotive force so high that accidental contact of the testing-electrodes with the person of the user or with 15 other conductors may cause serious shocks or discharges, and the electrodes must therefore be handled with great caution.

The object of the present invention is to 20 provide means whereby the contact-members of the electrodes are so shielded that accidental contacts are rendered practically impossible, while at the same time the use of the electrodes is not made in any degree 25 inconvenient. To this end it is proposed to provide a testing-electrode with an insulating shield which is in position to guard the contact-member whenever the electrode is not in actual use, but which is automatically 30 withdrawn and held out of the way in consequence of the act of grasping the electrode for the purpose of using it.

The idea in question may be embodied in various ways, but the preferred embodiment 35 is illustrated in the accompanying drawings, in which:

Fig. 1 is a longitudinal sectional view of a testing-electrode, with the parts in the position occupied when not in use; Fig. 2 is an 40 end-elevation, looking from left to right in Fig. 1; and Figs. 3 and 4 are enlarged sectional views on the lines 3-3 and 4-4 in Fig. 1.

In the illustrated electrode the contact-member is a metal rod 5 with a pointed end; and the guard has the form of a tube 6 of insulating-material such as vulcanized fiber. The electrode is handled and controlled by two grip-members 7 and 8. The member 7 45 is clamped to the guard by means of a screw 9. The member 8 has a tubular hub or sleeve 12 which slides freely on the guard at a point where the latter is provided with a longitudinal slot 10. A cross-pin 11, of 50 fiber or other insulating-material, is fixed

in the sleeve 12 and it passes through the rear end of the contact-rod 5, thus connecting this rod with the grip-member 8.

A coiled spring 13, attached to the rear end of the rod 5, serves both to retract the rod within the guard, and to connect it with an electric conductor. A metal nipple 14 is screwed into the rear end of the guard-tube 6, and a cap 16 is threaded upon the rear end of the nipple, this cap being of insulating-material. A loose metal bushing 18, with a conical rearwardly-opening socket, is enclosed by the cap, and a flexible cable or conductor 15 has its conductive core soldered or otherwise connected with this bushing. 65 A split conical bushing 17 cooperates with the bushing 18, so that when the cap 16 is screwed home the cable 15 is firmly gripped and clamped in place. By the same operation the bushing 18 is pressed against a 70 cross-pin 19 to which the rear end of the spring 13 is attached, thus completing the conductive connections between the contact-rod 5 and the cable 15.

When the electrode is not in use the spring 80 acts to hold the contact-rod retracted within the guard, as shown, but when the grip-members are grasped they are thereby drawn together, thus sliding the rod forwardly so that its end protrudes from the 85 guard. In this position the two grip-members constitute substantially a single handle of convenient form, and the electrode can be used precisely the same as the ordinary unguarded electrode. The moment the electrode is dropped or laid down, however, the contact-rod is automatically withdrawn in 90 to a position of safety.

The invention claimed is:

1. A testing-electrode comprising: a 95 guard; a contact-member movable, relatively to the guard, into and out of a position in which it is shielded by the guard; a spring tending to move the contact-member into shielded position; and grasping-means, suitable for manipulating the electrode, connected with the guard and the contact-member and movable, in consequence of being grasped in the hand of the user, to cause movement of the contact-member into operative, unshielded position.

2. A testing-electrode comprising: a tubular guard of insulating-material; a contact-rod slidably mounted in the guard; a spring 100 tending to retract the contact-rod within the 11

- guard; and a handle connected with the rod and movable in consequence of being grasped in the hand of the user, to cause the rod to protrude from the guard.
- 5 3. A testing-electrode, as set forth in claim 2, in which the said handle comprises two grip-members attached, respectively, to the guard and the contact-rod and movable toward each other when grasped.
- 10 4. A testing-electrode comprising: a tube, of insulating material, with a transverse slot near its rear end; a contact-rod slidable within said tube; a sleeve slidable upon the outside of the tube; a pin connecting said rod and sleeve through said slot; a grip-member projecting laterally from the sleeve; a second grip-member fixed to the tube; and a spring for moving the contact-rod in a

direction to retract it within the tube and to separate the grip-members. 20

5. A testing-electrode comprising: a tube tube of insulating material; a contact-rod normally housed, at its forward end, within said tube but slidable therein to cause said end to protrude from the tube; a grip-member rigidly attached to the tube and extending substantially at a right angle therefrom; a member attached to the rod, slidably guided by the tube and provided with a second grip-member substantially parallel with the first said grip-member; and a spring interconnecting the tube and the slidable members and acting to retract the rod within the tube. 25 30
